UNITED STATES PATENT OFFICE.

SYLVANUS B. CRANE, OF KANSAS CITY, MISSOURI.

WINDOW-SASH HOLDER.

1,044,144.

Specification of Letters Patent.

Patented Nov. 12, 1912.

Application filed October 10, 1910. Serial No. 586,308.

To all whom it may concern:

Be it known that I, SYLVANUS B. CRANE, a citizen of the United States, residing at Kansas City, in the county of Jackson and 5 State of Missouri, have invented certain new and useful Improvements in Window-Sash Holders; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification. 15 My invention relates to window sash holders and more particularly to a device of that class by which the window sash will be frictionally held at the desired height in the window frame without the aid of 20 counterbalancing weights.

The principal object of my invention is to provide a window sash with a holder having a friction block which may be automatically thrown into and out of additional 25 frictional engagement with a bearing strip according to the direction of movement of the window sash, so that the window sash may be easily raised; but will be frictionally and yieldingly held at the desired height 30 when released.

A further object of my invention is to provide other new and improved details of construction hereinafter described and illustrated in the accompanying drawings, in 35 which:—

Figure I is a vertical section of a window frame and sash illustrating my improved frictional sash holder; a part of the sash friction strip being broken away to show 40 the friction devices. Fig. II is a vertical section on the line II—II of Fig. I, showing a part of a lower window sash provided with my frictional sash holder. Fig. III is a vertical section of my frictional sash 45 holder. Fig. IV is a vertical section of the upper part of a window sash showing a preferred form of yielding keeper or latch. Fig. V is a detail perspective view of the friction block; a part of a lower corner being 50 broken away for better illustration.

Referring more in detail to the parts:— 1 is a window frame in which are mounted the window sashes 2 and 3 which are adapted for sliding movement in said window frame 55 in the usual manner.

Spaced inwardly to a distance less than

the width of the sash stile is a friction strip 4, which is secured to the bearing strip 5 and is adapted to lie parallel to the side of the window frame 1, fixedly mounted on the sash 2 and slidably mounted between the side of the window frame and the friction strip 4 is a bracing device comprising a pair of flat side springs 7 and a friction block; the ends of the side springs 7 being 60 bent outward and curved inwardly at their extremities to frictionally engage the faces of the window frame 1 and the friction strip 4, respectively, and the central portion being united by a pivot pin 9 upon which the 65 friction block is pivotally mounted. The springs 7 are also freely rotatable with respect to the friction block. Said friction block is adapted to impinge against the bearing strip 5 and is preferably of hollow 70 or skeleton construction and comprises the side portions 10 and a front face having a lower vertical portion 11 that is parallel with the free edges of the sides, and a slanting upper portion 12 that is continuous with 75 and extends above the vertical front portion 11. Extending partly across the bottom of the friction block is the base 13 the use of which will be presently described.

15 is a flat front spring, one end of which 80 is fixed to the lower end of the face of the window sash rail while the other end is left free and has frictional engagement therewith, the central part being bowed outwardly and cut away at its edges to form a 85 neck 16 providing lower and upper offsets or shoulders 17; the upper offsets being located substantially nearer the center of the bowed part of the front spring 15 than the lower offsets 17, see Fig. II. The neck 90 16 of the front spring 15 is adapted to slide within the friction block between its pivot pin 9 and the front portion thereof and the front spring is also adapted to carry the friction block with it when the offsets 17 95 come in contact therewith; the friction block being frictionally supported by the side springs 7 of the bracing device.

At the upper end of the window sash rail I place a spring member 18, one end of which 100 is rigidly fastened to the face of the window sash rail while the other end is bent outwardly and carries an anti-friction roller 19 that is adapted to bear against a metal strip 20 on the face of the bearing strip 5 110 for the purpose of keeping the upper portion of the window sash against its guide

member 21. In the upper rail of the window sash I provide one or more spring latches or keepers comprising a plunger 22, which is carried in a socket 23 and tensioned 5 against a metal latch plate 24 in the cross frame member 25 by a spring 26. When the window sash is at rest in its lowest position the vertical front portion of the friction block 11 is caused to impinge 10 against the face of the bearing strip 5 by the bowed portion of the front spring 15 bearing against the inner edge of the base 13 of the friction block which is frictionally supported normally by the lighter side 15 springs 7 against the upper offsets 17 of the front springs 15. When the window sash is raised the side springs 7 are frictionally bracing and supporting the friction block, as hereinbefore stated, so that the neck 16 20 of the front spring 15 slides through the friction block against the pivot pin 9 of the friction block and the friction block following the inward curvature of the front spring 15 draws the vertical front portion 11 of the friction block away from the face of the bearing strip 5 and tilts the friction block and the lower shoulders 17 of the front spring 15 next coming in contact with the friction block lifts the friction block with 25 the side springs 7 by overcoming the frictional hold of the latter on the window frame 1 and the friction strip 4. As the window sash is moved upwardly the inner edge of the base 13 follows the curve of the front spring, the lower front portion 11 of the friction block is tilted inwardly on its pivot pin 9 while the upper slanting portion 12 is tilted outwardly toward the metal strip 20 on the face of the bearing strip 5 30 and may slide thereon freely to its upper position. When the window sash reaches its highest position the side springs 7 will hold it up frictionally. When the window sash is lowered the side springs 7 will yield and 35 slide on the window frame 1 and the friction strip 4, the neck 16 of the front spring 15 will slide in the friction block and its bowed portion, coming in contact with the edge of the base 13 of the friction block, 40 will tilt the latter and the continued downward movement of the window sash will cause the upper stops 17 on the front spring 15 to engage the friction block so as to cause the lower vertical front portion 11 of the 45 latter to bear on the bearing strip for steady- 50 ing the downward movement of the window sash.

Owing to the lower offsets 17 being low down on the bowed part of the front spring 55 15, the vertical front portion 11 of the friction block will be pressed but lightly against the bearing strip 15 so that it will exert but little resistance to the upward movement of the window sash. The side springs 7 are 60 only of slightly greater strength than is

necessary to hold the weight of the window sash so that when the window sash is to be lowered, a slight downward pressure thereon will overcome the frictional hold between the window frame 1 and the friction strip 4, so that the window sash can be easily lowered against the tension of the springs. 70

In use I prefer to have a spring 18 and roller 19 at the top and my frictional device at the bottom of one side sash rail and like parts located vice versa on the opposite sides of the window sash rail in order to more evenly balance the window sash. 75

Having thus described my invention the 80 following is what I claim as new therein and desire to secure by Letters Patent:

1. A window sash holder, comprising a spring member having stops and a bowed portion between its ends, and a friction 85 block slidably mounted on the bowed portion between the stops.

2. A window sash holder, comprising a spring member having stops and a bowed portion between its ends, a friction block 90 slidably mounted on the bowed portion between the stops, and yielding means for retarding travel of the block.

3. A window sash holder, comprising a spring member having stops and a bowed 95 portion between its ends, a friction block slidably mounted on the bowed portion between the stops, and an auxiliary spring member for yieldingly retarding travel of the block. 100

4. A window sash holder comprising a bowed spring having a contracted portion between its ends and shoulders at the ends of the contracted portion, and a friction block 105 slidably mounted on the contracted portion and adapted for abutment against said shoulders.

5. A window sash holder comprising a spring having a bowed portion between its ends and stop members at the ends of the bowed portion, and a friction block having a closed side and a pin spaced from the side whereby the block is mounted for slidable and pivotal movement on the bowed portion of the spring between the stop members. 110 115

6. A window sash holder comprising a spring having a bowed portion between its ends and stop members at the ends of the bowed portion, and a friction block having a closed side and a pin spaced from the side 120 whereby the block is mounted for slidable and pivotal movement on the bowed portion of the spring between the stop members, the closed side of the block having a vertical and an inclined face for the purpose set forth. 125

7. A window sash holder comprising a pivot pin, a friction block mounted on the pivot pin, a pair of side springs mounted on the friction block, and a front spring having a neck, providing shoulders and 130

passed through the friction block between the pivot pin and the front portion of the friction block.

8. A window sash holder comprising in combination with a window frame and window sash, a bearing strip secured to the window frame, a spring secured at one end to the window sash and adapted for yielding contact with said window sash at the opposite end, a friction block slidably mounted on said spring and adapted for engagement with said bearing strip, a friction strip, and friction members carried by the friction block and engaging the window frame and friction strip respectively.

9. A window sash holder comprising in combination with a window sash, a bearing strip secured to the window frame, a flat spring secured at one end to the window sash and having a central bowed portion, a friction block carried by the bowed portion of said flat spring and adapted for both pivotal and sliding movement thereon, a friction strip, and springs carried on opposite sides 25 of said friction block and engaging the window frame and friction strip respectively.

10. A window sash holder comprising in combination with a window frame and window sash, a bearing strip fixed to the window frame, a spring fixed at one end to the window sash and having a central bowed portion, a friction block comprising a verti-

cal face and an inclined face, a pin extending transversely between the sides of the friction block and retaining the latter on said spring, a friction strip, and friction members carried on opposite sides of the friction block and engaging the window frame and friction strip respectively.

11. A window sash holder comprising in combination with a window frame and window sash, a bearing strip fixed to the window frame, a flat spring fixed at one end to the window sash and having a central bowed portion of less width than the remainder of the spring body providing a neck and shoulders, a friction block carried on the bowed portion of said flat spring and through which the neck of the spring is 50 adapted to slide, said friction block having side portions, a vertical face, an inclined face, and a base member extending partly beneath said side portions, a pin extending between the side portions, a friction strip, and springs secured to the side portions and having out-turned ends engaging the window frame and the friction strip respectively.

In testimony whereof I affix my signature 60 in presence of two witnesses.

SYLVANUS B. CRANE.
